FURNACE FOR METAL WORKING

John Schmeller, Sr., Lakewood, Ohio, assignor to
 Schmeller Holding Company, Cleveland, Ohio,
 a corporation of Ohio

Application March 31, 1930, Serial No. 440,508

6 Claims. (Cl. 263—23)

This application is a continuation in part of my application, Serial No. 252,738, filed February 8, 1928. This invention as indicated relates to a furnace for metal working. More particularly it

- 5 has in view the provision of an apparatus especially adapted for the deoxidizing and refining of light, readily oxidizable metals, such as aluminum, and the like, and the recovery of the same from salvage materials including finely divided 10 material such as borings, turnings, skimmings, sweepings, and the like. The furnace may be one of a unit of metal treating chambers similar to that shown in my Patent No. 1,659,445 or applications co-pending therewith.
- 15 It is well known that the elimination of oxides from metals in a molten state is involved in much difficulty, and especially so with finely divided metal particles of light, readily oxidizable metals, such as aluminum, because of the relatively large 20 amount of oxide surrounding the individual particles of metal.

The present apparatus has in view the treatment of metals in a molten state, especially light metals, as above described, in such a manner that 25 the deoxidizing of the same and the freeing of the mass from impurities may be carried on with a high degree of speed and with a resulting product having a minimum residual amount of oxides and impurities therein. To the accomplishment of the foregoing and related ends, said invention, then, consists of the means herein- 30 after fully described and particularly pointed out in the claims.

The annexed drawing and the following description set forth in detail certain mechanism embodying the invention, such disclosed means constituting, however, but one of various mechanical forms in which the principle of the invention may be used.

40 In said annexed drawing:

Fig. 1 is a central vertical view partly in section, showing a form of construction embodying the principles of my invention; and Fig. 2 is a transverse central sectional view of the device shown in Fig. 1, looking toward the right.

45 As is clearly shown in the drawing, the furnace 1 includes a chamber which may be designated a melting or puddling chamber 2, which communicates through a small opening 3, adjacent its base with an adjoining chamber 4, which may comprise a casting or heating chamber, similar to that in my application heretofore referred to, to receive the metal treated in the chamber 2, and bring it to or maintain it at the proper temperature for casting. The furnace chamber 4

may also be used as an intermediate chamber for further treatment of the metal preliminary to changing the same into castings or ingots.

The melting and puddling chamber 2, as shown in the drawing, is provided with a suitable supporting base 5, of masonry or the like, upon which the floor 6 of the puddling chamber rests. The bottom of the melting and puddling chamber is substantially semi-circular as seen in cross-section, and merges with the vertical side walls 7, 8, which support a roof 9, of suitable material. End walls 11, 12, are also provided, the inner end wall 11 being provided with the small opening 3 communicating with the adjoining chamber 4.

The outer end wall 12 is provided with a large opening 13 shown as rectangular in form, and having a small channel or recess 14 on its under side for a purpose to be presently explained. A heavy explosion door 15 of suitable refractory material is adapted to be hung over said opening, 70 said door being preferably supported on flexible members 16, and movable outwardly by the pressure of the gases within the melting and puddling chamber. The weight of the explosion door is such that the egress of the gases therefrom will 75 be retarded and inasmuch as all the furnace openings in the melting and puddling chambers are covered with heavy doors, there will be incomplete combustion of the gases within said chamber which will be held over the molten mass at a slight 80 degree of pressure. Thus the access of oxygen to the molten mass is prevented. The reducing gases held above the bath may be produced from the oil and grease on the particles of material being treated, such as borings, turnings, and the 85 like, or may be introduced through oil jets (not shown). As stated, the melting and puddling chamber 2 is in communication with the adjacent chamber 4 through the opening 3 and the heat applied by oil or gas jets to the metal in the chamber 90 4 is communicated to the metal undergoing agitation in the puddling chamber.

At the sides of the furnace charging and skimming openings 17, 18, with suitable doors 19, 20, preferably suspended on flexible members, are 100 provided so that the material to be treated may be fed into the furnace at either or both sides as may be found desirable. Either side may be used as the feeding or skimming side, as may be most convenient. Suitable troughs 21, 22, are provided below the respective openings 17, 18, to receive any skimmings or refuse. If desired, said troughs may contain a quantity of water. The recess 14 adjacent the lower portion of the explosion opening provides for the free passage into the melting 105 110

and puddling chamber of a horizontal shaft 23 supporting the agitating grid 24 at its free end. The shaft is supported in a suitable bearing 25 mounted upon a pedestal 26 spaced some distance 5 from the furnace so as to keep said bearing at all times free from deterioration owing to the heat of the furnace gases. The grid or agitating member carried by the shaft may assume various forms and may comprise a single grid or plate, as 10 illustrated, or may be formed of a plurality of plates, as will be obvious. Likewise the grid may be oscillated back and forth through the molten metal or it may be rotated therethrough, by any conventional crank arm 40 or gears (not shown), 15 associated with a suitable motor.

If at any time it should be necessary to withdraw the grid from the furnace structure, the same may be rotated to a vertical position upwardly above the shaft and withdrawn outwardly 20 through the explosion door above the recess referred to. The explosion door 15 is provided with a notch 27 centrally of its lower edge which permits said door to serve as a partial closure for the excess space about the opening for the shaft.

25 The grid preferably has a minimum degree of clearance from the side walls and bottom wall of the furnace chamber and preferably has apertures 30 of such size that a fair degree of speed of movement through the molten mass may be 30 carried out and yet thorough agitation of said mass produced.

35 The shaft is normally disposed above the level of the liquid within the furnace chamber and as it is oscillated or rotated, the grid is forced through the molten mass of metal. Oscillating motion is preferable in most instances as it permits more frequent agitation and is self-cleansing of adhering particles. This puddling action breaks up the molten mass into a series of subdivisions which, through the mechanical action of 40 the grid by friction and impact, serves to separate the particles of added material and intermix them with the mass of molten metal within the chamber whereby thermal as well as mechanical action will be had upon the individual particles and the metal will be incorporated with the molten heel or body of metal originally within the furnace, the oxides and foreign matter being freed therefrom and rising to the surface from which 45 they may be removed by skimming from time to time. The pure metal may be drawn from the furnace into the chamber 4 through the opening 3 adjacent the base thereof. In order to permit the withdrawal of material at the bottom of the 50 melting and puddling chamber, a downwardly inclined passageway 28 is formed through the outside end wall of the chamber at the bottom thereof which also assists in the cleaning of the melting and puddling chamber of any accumulated 55 foreign matter. A suitable plug 29, of clay or the like, may be used to close the opening during 60 normal operation of the furnace.

65 Other modes of applying the principle of my invention may be employed instead of the one explained, change being made as regards the mechanism herein disclosed, provided the means stated by any of the following claims or the equivalent of such stated means be employed.

70 I therefore particularly point out and distinctly claim as my invention:

75 1. An apparatus of the character described having in combination a furnace chamber adapted to receive a bath of molten metal and having straight end walls and a base portion of semi-circular cross-section, a shaft mounted

concentrically with said semi-circular portion, and agitating means in the form of a grid extending substantially the full length of said chamber and adapted to be partially immersed in the molten metal of said bath secured to said shaft and having its marginal end portions in closely spaced relation to the respective straight end walls of said chamber and its lower margin in closely spaced relation to the curved portion of said furnace chamber.

80

2. An apparatus of the character described having in combination a furnace chamber adapted to receive a bath of molten metal and having straight end walls and a base portion of semi-circular cross-section, a shaft mounted concentrically with said semi-circular portion, a grid extending substantially the full length of said chamber and adapted to be partially immersed in the molten metal of said bath secured to said shaft and having its marginal end portions in closely spaced relation to the respective straight end walls of said chamber and its lower margin in closely spaced relation to the curved portion of said furnace chamber, and means for moving said grid into and out of contact with the bath of molten metal positioned within said semi-circular portion of said furnace chamber.

85

90 3. An apparatus of the character described having in combination a furnace chamber adapted to receive a bath of molten metal and having straight end walls and a base portion of semi-circular cross-section, a shaft mounted concentrically with said semi-circular portion, agitating means in the form of a grid extending substantially the full length of said chamber and adapted to be partially immersed in the molten metal of said bath secured to said shaft and having its marginal end portions in closely spaced relation to the respective straight end walls of said chamber and its lower margin in closely spaced relation to the curved portion of said furnace chamber, and a substantially closed superstructure for said furnace chamber to substantially seal said shaft and to retain reducing gases above said bath of molten metal.

95

100 4. An apparatus of the character described having in combination a furnace chamber adapted to receive a bath of molten metal, the lower portion of which is of semi-cylindrical outline and the upper portion of which is enclosed by a housing having a plurality of apertures closed by suspended doors in close contact therewith and freely movable outwardly under pressure of gases within said furnace, a shaft supported independently of said furnace and projecting thereinto from one end to a point substantially adjacent the farther wall thereof and agitating means secured to said shaft, said means comprising a plurality of members with open spaces between the same through which the metal is forced by the movement of said means, and subdivided into a plurality of separated portions which react upon each other.

105

110 5. An apparatus of the character described having in combination a substantially closed furnace chamber, having a large opening adjacent one side closed by an explosion door, and providing a recess on the lower side of said opening, an agitating member comprising a grid member mounted on a shaft, said grid being adapted to be engaged within said furnace through said large opening with the shaft seated in said recess, and means spaced from said furnace adapted to form the sole support of said agitating member.

115

120 6. An apparatus of the character described

125

having in combination a substantially closed furnace chamber provided with means to hold a bath of molten metal, an agitating member in the form of a grid entering said chamber through a side wall thereof and supported exteriorly thereof and having small clearance about its free margins from the furnace walls, and means for moving

said agitating member from a position above the liquid level at one side through the mass of molten metal in a direction at an angle to the surface of said metal to a position above the liquid level at the opposite side.
